THREAD-TENSIONING DEVICE

Frank B. Javery, Worcester, and Armon J. Javery, Oxford, Mass., assignors to Warp Compressing Machine Company, Worcester, Mass., a corporation of Massachusetts

Application May 2, 1931. Serial No. 534,560

4 Claims. (Cl. 242—147)

The present invention relates to thread tensioning devices of the type employing rotatable whirls, or pulleys, around which filamentary material or thread is drawn at high speed with the 5 frictional retardation of the whirls creating the desired amount of tension in the moving thread.

The principal object of the invention is to provide a thread tensioning device of the above indicated character which will operate satisfactorily 10 at extremely high speeds, without vibration, with the result that the pull on the filamentary material is always constant. Further objects are to provide a device which does not permit chafing of the moving material, by crossing, and which 15 prevents the accumulation of lint or loose fibers.

In handling filamentary material of a silky nature in which the fibers are very fine and fragile, as in the well known rayon thread, any vibration or uneven rotation of a whirl will subject the 20 thread to jerks or strains which tend to pull apart or stretch the delicate fibers; and any such strains are substantially eliminated according to the present invention. In carrying out the invention, a pair of whirls preferably cylindrical in form are 25 mounted to rotate freely about slightly converging axes, the filamentary material being wrapped around both whirls, and it has been found that this device may be operated at extremely high speeds, without vibration and without straining 30 the thread. In operation, the turns of thread have a tendency to move toward the proximate ends of the whirls which prevents any crossing of the moving thread tending to fray or break the material. This tendency of the threads to 35 work towards the ends of the whirls also prevents excessive wear on any particular portion of the whirls, thereby lengthening the life of the device. Other and further advantages of the present invention will appear from the following description 40 in connection with the accompanying drawing, in which:—

Fig. 1 is a plan view of a series of improved thread tensioning devices in use on a creel.

Fig. 2 is an enlarged plan view of one of the 45 tensioning devices shown in Fig. 1.

Fig. 3 is a side elevation of the device in Fig. 2, parts being broken away to show the construction thereof.

Fig. 4 is an enlarged section along the line 4—4 50 of Fig. 2, the whirls being removed from the spindles.

Fig. 5 is a plan view of one of the whirls.

Fig. 6 is a fragmentary view in elevation, illustrating the lint clearing action of a whirl.

Fig. 7 is a fragmentary sectional view of a spindle and whirl assembly.

Like reference characters refer to like parts throughout the drawing.

Referring first to Fig. 1, a series of thread 60 controlling and tensioning devices 1 embodying the invention are mounted on a horizontally extending member 2 forming part of the frame work of a creel or spool stand of usual construction. Separate filaments or threads 3 are adapted to be 65 drawn from a series of packages 4 corresponding in number and spacing to the tensioning devices 1, each thread passing through a guide 5 mounted on the frame member 2. Each guide 5 is symmetrically disposed with respect to a tensioning 70 device 1, and after passing around a device 1 in a manner to be hereinafter described, each thread 3 passes through a second guide 6 disposed at right angles to the guide 5. All of the guides 6 are in substantial alignment so as to deliver the 75 threads 3 for winding on a suitable spool or warp beam, not shown, the several tensioning devices 1 serving to maintain a constant tension on the threads 3 during the winding.

Each tensioning device 1, as best shown in Fig. 80 2, comprises a supporting guard plate 7, preferably of sheet metal, providing oppositely projecting ears 8 by which the plate is connected to and supported between the frame member 2 and a bar 9 spaced from and extending parallel to the member 2. The plate 7 is further provided with a pair of spaced circular openings 10, see Fig. 4, in which are received the lower portions of a pair of cylindrical whirls or drums 11, the openings 10 being of such diameter as to provide ample clearance 85 for the drums 11, as shown in Fig. 7. A portion of the plate 7 surrounding each opening 10 is depressed below the plane of the plate to provide an arm 12 carrying a spindle 13 for rotatably supporting a drum 11, and as best shown in Fig. 4, 90 one arm 12 is bent downwardly with respect to the opposed arm, so that the axis of rotation of one whirl 11 is inclined with respect to the other whirl for a purpose which will hereinafter appear. The plate 7 provides at one end a projecting portion 95 14 which is bent upwardly at right angles to the plane of the plate, and provides an opening for receiving a thread guide 6 through which a thread 3 is drawn after passing around the whirls.

As best shown in Fig. 2, each whirl spindle 13 is 100 preferably triangular in cross-section with its corners rounded to substantially correspond to the curvature of the cylindrical bore 11a of the whirl, each spindle 13 being secured to its supporting arm 12 by a screw 15. This particular 110

construction of the spindles 13 forms no part of the present invention per se, as the construction is shown and described in our copending application, Serial No. 489,952, filed October 20, 1930. 5 As fully set forth in our copending application, noted above, this particular type of spindle construction insures free rotation of the surrounding whirl 11 without substantial vibration, and the present invention contemplates an arrangement 10 for tying the spindles 13 together in pairs to eliminate any possible vibration of their upper portions. To this end, a tubular washer 16, preferably composed of rubber, is mounted in a seat 17 provided in the upper end of each spindle 13 and 15 a U-shaped connecting member 18 having its legs pressed into the washers 16 serves to secure the spindles 13 together. With this arrangement, any tendency for the spindles 13 to vibrate due to the rotation of the whirls at high speed, is effectively prevented by the cushioning action of the 20 resilient washers 16.

Each whirl 11 preferably comprises a hollow cylindrical drum portion having an enlarged head 19, the outer surface of the drum portion 25 being covered with a thin layer 20 of frictional material such as spongy rubber. The whirls 11 are mounted to rotate on the spindles 13 with the lower edges of the drums resting upon felt washers 21 which surround the lower ends of the 30 spindles and are supported by the arms 12. It will be noted that the rubber covering 20 on each whirl 11 extends below the plane of the upper surface of the guard plate 7, so that if the rotation of the whirl ceases at any time, as by breakage of the thread, and the thread continues to run out and loosen on the whirls, the guard plate 7 will support the loosened turns of the thread. It has been found that thread like rayon always 35 tends to run out following a stoppage so that 40 when the operation is resumed, any loose turns of thread supported on the plate 7 automatically resume their correct position on the whirls.

In the construction shown in detail in Figs. 5 and 6, there is shown a structure by which lint 45 or short loose fibers of the filamentary material are prevented from wrapping around the whirls 11. The head 19 of each whirl 11 is provided with a pair of helical slots 22, extending through the 50 head, the slots 22 being cut in such a direction that a downward draft will be created over the cylindrical drum of the whirl as it rotates. This 55 downward draft passes over the portion of the whirl on which the thread runs, as indicated by the arrows in Fig. 6, so that lint or other material carried by the thread is blown away from the whirl surface.

In the operation of a tensioning device 1, the 60

thread 3 as drawn from a yarn package 4 through a thread guide 5, which is positioned adjacent the lower end of the spindles and above the guard 7, passes onto the right hand whirl 11 and is then wound around both whirls 11 a plurality of times, 80 as shown in Fig. 3. The number of turns taken around the whirls depends upon the clinging effect of the material and the strength thereof, and it should be noted that the second thread guide 6 is disposed above the first guide 5 in the 85 direction of convergence of the spindle to compensate for the climbing action of the moving thread, due to the convergence of the spindle axes. As the whirls rotate at high speed, the friction between the whirls and spindles and between the whirls and felt washers 21 provides sufficient retardation to maintain a substantially constant and even tension on the thread as it leaves the whirls. Furthermore, as the thread tends to climb on the inclined whirl the several 90 turns are spaced apart, without crossing, thereby preventing any chafing and distributing the 95 wear on the drum coverings 20.

We claim,

1. In a thread tensioning device, a pair of cylindrical drums freely rotatable about converging axes, said drums providing smooth outer surfaces, means for leading filamentary material to said drums, and other means for leading the filamentary material from said drums, said latter 105 means being spaced from said first means axially of said drums in the direction of convergence of the axes of said drums, whereby turns of the material passing around said drums are separated.

2. In a thread tensioning device, a pair of spindles mounted in convergent relation, a pair of cylindrical drums mounted for free rotation on said spindles, and yielding means connecting the upper ends of said spindles and supporting 110 said ends in spaced relation.

3. In a thread tensioning device, a cylindrical rotatable drum having a head adjacent one end thereof, with said head projecting beyond the surface of said drum, said head providing a substantially helical slot extending inwardly from 120 the periphery of said head to create a draft over the cylindrical surface as the drum rotates.

4. In a thread tensioning device, a pair of cooperating cylindrical drums rotatable about substantially vertical axes and a guard surrounding said drums adjacent to and above the lower ends of said drums, said guard serving to prevent filamentary material passing around said drums from dropping away when in a slack condition.
